CLAMPING DEVICE FOR PAPERHANGERS' OUTFITS

Mortimer C. Harrison, Chicago, Ill.

Application April 25, 1940, Serial No. 331,527

10 Claims. (Cl. 24—248)

This invention relates to a clamping device for paperhangers' outfits, including table or bench boards, trusses, horses or props and a straight edge of wood or metal.

Still another object of the present invention is to provide an improvement upon the device shown in my prior application, Serial Number 324,648, filed March 18, 1940 so as to tightly clamp paperhangers' boards and accessories or supplemental members of paperhangers' outfits irrespective of the variations in the thickness of the boards. I have found that there are many different thicknesses in paperhangers' boards and also that the straight edges vary a small degree in thickness. Some paperhangers have gone to the trouble of having extra heavy boards made specially for them to give greater rigidity or stiffness and these boards are much heavier than the stock sized boards ordinarily sold as part of paperhangers' outfits. The old style clamps did not effectively accommodate and hold the boards and straight edges under such circumstances and the present clamp is designed to take care of these differences.

Another object of the invention is to avoid bending or flexing of the top part of the clamp under stress and to so reinforce the same that it will be kept comparatively rigid or prevented from bending and thus give an even bearing on the trestles and straight edge when in clamping position.

Another object of the invention is to provide a rubber or cushion packing which will take up the difference in thicknesses of said edges and trestles, this being provided on the top part of the clamp to permit the spaces between said edge and the trestles to be any desired width so that the pressure on the rubber against the straight edge and trestles will firmly hold these parts and avoid mutilation thereof.

Still another object of the invention is to provide an improved clamping means for opposite ends of the clamping device so that the parts will be retained positively in clamping positions after being once adjusted according to the thickness of the parts.

Still another object of the invention is to provide a novel clamping device of the above character which will facilitate packing thereof in a compact folded or collapsible condition; which will keep the boards straight; which will hold a wood or steel straight edge firmly and prevent its displacement as well as avoid injury or mutilation to any of the parts or loss of same and will avoid the necessity of having holes in the

board or straight edge in addition to being very simple and capable of being quickly applied or removed.

Further objects and advantages will appear and be brought out more fully in the following specification, reference being had to the accompanying drawing, in which:

Fig. 1 is a plan view of a paperhanger's outfit with the clamping devices applied and in use;

Fig. 2 is an enlarged transverse section taken on the line 2—2 of Fig. 1;

Fig. 3 is an end view looking toward the left hand end of Fig. 2, showing the hinge joint and clamping means;

Fig. 4 is an end view looking toward the right hand end in Fig. 2, showing the clamping means;

Fig. 5 is a plan view of the structure shown in Fig. 2;

Fig. 6 is an elevation of a clamping device with one end swung up 90 degrees and turned at right angles thereto 90 degrees; and

Fig. 7 is a sectional view of the upper member of the clamp taken on the line 7—7 of Fig. 5.

Referring to the drawing and more particularly to Figs. 1 to 6 inclusive, 10 designates an ordinary paperhanger's outfit for which the present clamping device or clamp is devised to hold the outfit in compact form when not in use for transportation or storing purposes, and at the same time permit the outfit to be readily taken apart and assembled or set up for use. This outfit includes table or bench boards 11, usually three in number having dowel pins 12 extending from one edge of each board and entering correspondingly located sockets 13 on the other edge of said boards so as to form one working surface. The bench or table is designed to be supported on collapsible or foldable supports in the form of horses, props or trestles 14 shown collapsible in Fig. 1. The outfit also includes a straight edge 15 which may be of any suitable construction

such as metal or wood reenforced with metal strips along the edges and bearing a scale 16, usually six feet long along one edge and having a cutting groove 17 adjacent the opposite edge 15 to facilitate measuring and cutting of the paper. The clamping device or clamp proper includes an upper bar 18 and a lower bar 19 of suitable spring steel or other desired metal. These bars form jaws, and the lower bar 19 may be straight 50 or bowed up slightly, although when the device is applied it will assume a straight or rectilinear form against the face of one of the boards 11 in the manner shown in Fig. 2 of the drawing. The bar 19 is provided with a pair of turned up 55

ends 20 which are received in the sockets 13 of the boards 11. The upper bar 18 is provided with a pair of turned up 55

ears 20 at one end formed by providing a recess or bifurcation in said end and turning up the forked portions thus formed in circular formation. The opposite end is provided with similarly formed down turned ears 21.

The top or locking bar is designated at 18 and includes a vertical end portion 22 bent downwardly at right angles thereto and then bent or turned inwardly at right angles as at 23, both portions 18 and 23 having vertically aligned or registering circular holes 24 to take an I or T-bolt 25. Through the medium of a pivot or trunnion pin of an I or T-bolt 25 extending through the ears 20 in case a T-bolt is used, or ears 20 and the eye of the bolt where an eye bolt is used, the bars are pivotally connected to swing to clamping or open position as indicated in solid and dotted lines in Fig. 2 and as shown in Fig. 6. Extending at right angles to the portion 22 is a part 26 which is designated to clamp the straight edge 15, and then the bar 18 is bent outwardly at right angles as indicated at 27 and substantially parallel to the portion 23 to form a shoulder. This portion is then extended parallel to the part 26 and at right angles to the portion 27, as indicated at 28 and then inwardly or downwardly substantially at right angles as indicated at 29 parallel to the portions 22 and 27 but deeper than the latter portion to form a pocket 30. The purpose of making the portion 29 deeper or longer than the portion 27 is that the straight edge 15 is interposed between the boards and the portion 26 whereas the portion 31 at the free end of the top bar 18 which extends outwardly substantially at right angles to the portion 29, engages directly with the top board of the boards 11. The free end portion of the clamping end 31 has a slot 32 communicating with the end thereof and formed by bifurcating or forking said end to take an I or T-bolt 33, a pivot or trunnion 34 extending at right angles thereto at one end of each bolt 25 and 33 serving to pivotally connect the bolts in the ears 20 and 21 to the ends of the bar 19. The threaded ends 35 of the bolts 25 and 33 are designed to take lock nuts 36 beneath bar 18 and a clamping or locking nut 37 and a wing nut 38 are screwed on the threads 35 of the bolts above the bar 18, and when the clamp is applied to the outfit, as shown in the drawing, the bolt 33 is swung up into the slot 32 and the nut turned down to tightly clamp the parts of the outfit and prevent possible displacement thereof.

In order to reinforce the upper bar or clamping member 18, the latter is provided with a truss or bridge work reinforcement 39 consisting of a narrow strip of metal in the form of a bow, with an intermediate wood filler 40 between its intermediate portion and the part 28 riveted or otherwise secured thereto as at 41, so as to contact with the corner portions of the riser portions 27 and 29 at the ends of the part 28 and having the end portions 43 bent at obtuse angles and flat to engage the portions 26 and 31 to which they are riveted as at 44. Rubber or similar cushion strips 45 and 46 are glued to the under faces of the portions 26 and 28 to contact with the straight edge 15 and the trestles 14, as shown in Figs. 2 and 7. This will not only prevent injury to the latter parts, but will also accommodate trestles and the straight edges varying in thickness. Thus, it will accommodate extra heavy boards, although this is primarily taken care of by the vertical adjustment of the portion 22 on the bolt 25 by adjusting the nuts 36

and 37 up or down and the adjustment of the portion 31 and the bolt 33 by the nuts 36 and 38. The nuts 36 are set at the required adjustment and then by turning the nuts 37 and 38 down tightly against the parts 26 and 31, the device will be firmly clamped in position. In order to adjust the upper clamping member or bar 18, the latter is swung outwardly on the pivot 34, as shown in dotted lines in Fig. 2, and then turned on the bolt 25 as shown in Fig. 6, and inasmuch as the nut 36 cannot turn within or relative to the part 22, but will turn therewith, the nut 36 and the clamp member or bar 18 may be adjusted up or down to vary the space between it and the bottom clamping member or bar 19. In this way boards of much heavier stock than the boards ordinarily sold in conjunction with paperhangers' outfits may be accommodated and firmly clamped when the parts are assembled in folded condition. By having the top part of the clamp reenforced the top member will be kept straight or level and thus give an even bearing on the straight edge and trestles when folded into clamping position. The sponge rubber packing strips or cushions will allow the spaces between the straight edge and the trestles to be any width, as all pressure of the clamp is on the rubber pressing downwardly on the straight edge and trestles. At the wing nut side of the clamp the nut 36 under the slot 32 of the upper member will be adjusted in proper position or at a desired level with the boards so that the wing nut may be turned down very tight. This is very necessary in keeping the wing nut and bolt from getting knocked out of the slot and will hold the parts more firmly.

It will also be seen that this device obviates the necessity of having holes in the boards and straight edge and permits the straight edge to be clamped firmly along one edge or side of the boards instead of being disposed in the center, while the supports in the form of trestles, horses or props are clamped along side of the same. This is especially advantageous in clamping a metal straight edge as it will hold the same firmly and no holes are necessary in the boards or straight edge. This is due to the fact that the clamping action is stronger where the bars of the clamp are pivoted together. Also, by having the bolts fastened to the frame of the clamp any chance of the bolts being lost is eliminated as it is unnecessary to remove the nuts from the bolts and the bolts from the clamp bars as with the hold device.

While I have described and illustrated the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to secure by Letters Patent is:

1. A clamping device for paperhangers' outfits including a pair of hinged bars spaced apart in clamping position throughout their lengths and clamping means carried by one end of one bar and designed to engage the adjacent end of the other bar, at least one end of one bar being adjustably connected at the hinged end for adjustment to vary the space between the bars.

2. A clamping device for paperhangers' outfits

including a pair of hinged bars of thin strip metal spaced apart in clamping relation throughout their lengths, one bar being offset in stepped relation from the other bar to accommodate the paperhangers' outfit between the bars, a bolt hingedly attached to the free end of one bar and adapted to engage through a slot in the other bar, and clamping means on the bolt engaging on opposite sides of the slotted bar, the hinged connection of one bar with the other bar being adjustable along the connection to vary the spacing of the bars and adapted to be clamped in adjusted position.

3. A clamping device for paperhangers' outfits including a pair of hinged bars, one bar having riser portions, and clamping means carried by one end of one bar and designed to engage the adjacent end of the other bar, one bar being disposed in spaced relation to the other bar from a point adjacent its hinged end and having an opening near the free end thereof, and a bolt at the free end of the other bar to engage said opening and a nut on the bolt, one bar being adjustable along the hinged connection with the other bar.

4. A clamping device for paperhangers' outfits including a bar, another bar hinged to one end thereof and offset from the first bar adjacent said end, said second bar having angularly bent portions forming clamping portions, shoulders and a pocket and having an opening adjacent its free end, a bolt attached to the free end of the other bar to engage said opening, a bolt at the hinged connection of one bar, the other bar having slideable connection with said bolt, locking nuts on said bolts to limit the displacement of the latter bar toward the first bar and clamping nuts on said bolts to engage the top of the latter bar.

5. A clamping device for paperhangers' outfits including a bar, another bar hinged to one end thereof and offset from the first bar adjacent said end, said second bar having angularly bent portions forming clamping portions, shoulders and a pocket having three different risers and a slot at its free end, a bolt hinged to the free end of the other portion to extend substantially at right angles to the bars and engage the slot, the hinged connection between the bars comprising a shank member, the second bar having a bent portion and apertured to engage such shank for adjustment thereon, locking means to hold the bar in adjusted position and clamping means on the bolt and shank.

6. A clamping device for paperhangers' outfits comprising a bar, another bar having a depending and substantially at right angles with spaced apertured portions, a shank pivoted to the ad-

jacent end of the first bar and on which said end is adjustable toward and away from the first bar, said second bar having riser portions at different elevations forming shoulders and an intermediate pocket, locking means between the bars and clamping means to connect the ends of the bars against the locking means.

7. A clamping device for paperhangers' outfits including a bar, a second bar having angular offset portions and end portion extending substantially at right angles, a bolt pivoted to the adjacent end of the first bar and adjustably connected to said right angular portion to pivot with the bolt and rotatable for adjustment thereon, clamping and locking means between the bolt and the second bar, another bolt pivoted at the opposite end of the first bar and engaging a slot in the second bar, and clamping and locking means on the last mentioned bolt to engage upon opposite faces of the slotted end of the second bar.

8. A clamping device for paperhangers' outfits including a pair of hinged bars, one of said bars having riser portions, a truss for said bar with the riser portions comprising a bow-shaped strip of metal with an intermediate filler between the bow and adjacent riser portion and end portions secured to the other riser portions, cushion strips secured beneath certain of said riser portions adjacent the hinge and intermediately and clamping means carried by one end of one portion and having locking engagement with the adjacent end of the other bar.

9. A clamping device for paperhangers' outfits including a pair of bars disposed in spaced substantially parallel relation, means to pivotally and adjustably connect an end of one bar to the adjacent end of the other bar for adjustment to vary said spacing and to clamp same against movement in either direction, and means to adjustably connect and clamp the other ends of the bars against movement toward and away from each other.

10. A clamping device for paperhangers' outfits including a substantially flat bar, shanks hinged to the ends thereof, another bar having one end bent downwardly and then inwardly, said latter bar and inwardly bent portions being mounted on one shank for adjustment along the same, clamping means on the shank on opposite sides of the second bar, and clamping means on the other shank at opposite sides of the free end of the second bar, said free end being separable from its shank and clamping means to permit it to be swung away from the first bar.

MORTIMER C. HARRISON.
